CONTROL FOR AN ELECTRIC BLANKET

Robert O. Ernest, Oak Park, Ill., assignor to Sunbeam Corporation, Chicago, Ill., a corporation of Illinois

Application November 3, 1958, Serial No. 53,239

Term of patent 14 years

(Cl. D26—13)

Fig. 1 is a perspective view of a control for an electric blanket, showing my new design;

Fig. 2 is a front elevational view, to an enlarged scale;

Fig. 3 is a top plan view, to an enlarged scale;

Fig. 4 is a side elevational view, to an enlarged scale, the opposite side being substantially a mirror image thereof; and

Fig. 5 is a rear elevational view thereof.

I claim:

The ornamental design for a control for an electric blanket, as shown and described.
